UNITED STATES PATENT OFFICE.

PAUL C. HALDEMAN, OF COATESVILLE, PENNSYLVANIA, ASSIGNOR TO LUKENS STEEL COMPANY, OF COATESVILLE, PENNSYLVANIA, A CORPORATION OF PENNSYLVANIA.

INDICATOR FOR THE ADJUSTING SCREWS OF ROLLING MILLS.

Application filed June 21, 1920. Serial No. 390,687.

To all whom it may concern:

Be it known that I, PAUL C. HALDEMAN, a citizen of the United States, residing in Coatesville, Pennsylvania, have invented 5 certain Improvements in Indicators for the Adjusting Screws of Rolling Mills, of which the following is a specification.

My invention relates to certain improvements in means for indicating the position 10 of the main adjusting screws of a rolling mill and is especially adapted for large mills.

One object of the invention is to provide 15 a dial which can be mounted in a convenient position to the operator so that he may cooperate to the best advantage with the man manipulating the mill tables and also with the man who is operating the reverse engine that drives the mill.

A further object of the invention is to 20 construct a dial for indicating the position of the rolls so that the operator can concentrate his sight upon one point of comparatively small area and locate the exact position of the rolls and can ascertain the 25 distance between them in inches and fractions thereof.

In the accompanying drawings:

Fig. 1 is an end view showing a portion 30 of the rolling mill in dotted lines and the indicator and the mechanism for driving the same in full lines; and

Fig. 2 is a front elevation of sufficient of 35 a rolling mill illustrated by dotted lines and showing the dial and the operating mechanism therefor in full lines.

I have illustrated my invention as applied to a large mill for rolling plates, although it may be applied to any type of mill without departing from the essential 40 features of the invention.

1, 1 are the housings of the mill shown by dotted lines. 2 is one of the adjusting screws for raising and lowering the rolls, which are of the ordinary type and not 45 shown. These rolls are adapted to suitable boxes in the housings.

The screw 2 has a rectangular end slidably positioned in a passage of similar shape in a rotatably mounted member 2^a, the latter 50 carrying a driving gear wheel 3. In such construction, as the screw 2 turns and moves upwardly, it is free to move unrestrainably in the latter direction only. The gear wheel 3 meshes with a pinion 4 on a stud carried

by a bracket 5 which is secured to the housings shown in Figs. 1 and 2. Secured to or forming part of the pinion 4 is a gear wheel 6, which is slightly beveled and meshes with a beveled gear wheel 7 secured to a diagonal shaft 8 mounted at its upper end 55 in bearings 9 carried by the bracket 5. The lower end of the shaft 8 is mounted in bearings 10 and 11, projecting from a plate 12 secured to the rolling mill housing.

14 is an inner dial and 13 is an outer dial 60 surrounding the inner dial, as shown in Fig. 1. The inner dial is mounted on a shaft 15 adapted to bearings 16 on the plate 12. On this shaft is a worm wheel 17, which meshes with a worm 18, on the shaft 8, so that the 65 dial 13 is driven very slowly. The dial 14 is mounted on a spider 19 secured to a gear wheel 20 mounted on the shaft 15 and turning independently thereof. Meshing with this gear wheel 20 is an intermediate gear 70 wheel 21 on a shaft 22 adapted to bearings 23 on the plate 12 and on the shaft 22 is a beveled gear wheel 24 which meshes with a beveled gear wheel 25 on the shaft 8. This gearing is such that the outer dial 14 revolves at 75 a greater speed than the dial 13.

26 is a pointer secured to a bracket 27 projecting from the housings of the mill. The extreme end of this pointer 26 is bent down and is in line with the graduations on the 80 inner dial. 28 is a bracket secured to the housings of the mill and has a curved slot 29 in which is mounted a pointer 30. This pointer projects in line with the graduations of the outer dial can be adjusted so as to be 85 in a direct line with the pointer 26. By this means, the operator can see at a glance the position of the two dials in respect to their pointers. The graduations of the inner dial, in the present instance, indicate 90 inches, while the graduations of the outer dial indicate fractions of an inch.

31 indicates the pipes leading from any suitable lubricating system to the bearings. While I have shown this arrangement of 95 pipes, it will be understood that any suitable lubricating device may be used without departing from the essential features of the invention.

The apparatus is used in the following 100 manner: The adjusting screws 2 are turned by suitable mechanism to change the opening between the rolls of a rolling mill. The

adjusting screws at each side of the mill are turned in unison. The device hereinbefore described is connected so as to turn with one of these screws, as shown in the 5 drawings. The operator who controls the mechanism that operates the screws can stand at any convenient point in front of the dials and can raise or lower the upper roll of the mill so as to space the rolls accurately as the indicator indicates the space 10 in inches, as well as in fractions of an inch. This device is placed at a convenient point where the operator can cooperate with the man handling the mill tables, as well as the 15 man operating the reverse engine of the mill.

I claim:

1. In an indicating mechanism for rolling mills, the combination with a housing for the 20 rolls of said mill, of a roll adjusting mechanism mounted on an upper portion of said housing, an indicating dial mounted on a lower portion of said housing, a shaft, and means for operatively associating the opposite 25 ends of said shaft with said adjusting mechanism and with said dial, respectively, whereby the position of said rolls may be indicated on said dial.

2. The combination in an indicator for the 30 adjusting screws of rolling mills, of an adjusting screw mechanism, a gear wheel thereon, a shaft, gearing between the shaft and the gear wheel by which the shaft is turned, two dials, one located within the other, and 35 gearing between the dials and the shaft, the ratio between the gears for driving one of said dials being such that the dial will be turned comparatively slowly, while the ratio between the gears by which the other dial is 40 turned will be such that said dial will be rotated at a speed greater than the speed of rotation of the other dial.

3. The combination in an indicator for the 45 adjusting screws of rolling mills, of an adjusting screw mechanism, a gear wheel thereon, a diagonal shaft, a gear wheel at the upper end of said shaft, intermediate gears between the gear on the shaft and the gear on the adjusting screw mechanism, a shaft having 50 a dial thereon, a worm wheel on said shaft, a worm on the first mentioned shaft meshing with the worm wheel so that the dial will turn comparatively slowly, an outer dial, a gear wheel carrying said dial and mounted 55 loosely on the shaft of the inner dial, an intermediate shaft having a gear wheel thereon meshing with the dial gear wheel and having a bevel wheel at the opposite end of said shaft, and a bevel wheel on the shaft 60 with which it meshes so that the outer dial will revolve at a greater speed than the inner dial.

4. The combination in an indicator for the 65 adjusting screws of rolling mills, of an adjusting screw mechanism, a gear wheel there-

on, a diagonal shaft, a bracket supporting the upper end of the shaft, intermediate gears mounted on said bracket and through which motion is imparted from the screw mechanism to the shaft, a housing supporting the screw and the bracket, a plate secured to the lower portion of the housing, bearings on said plate for the lower end of the diagonal shaft, two dials, one located within the other, a shaft on which the lower dial is mounted, worm gearing between said shaft and the diagonal shaft so that the dial revolves comparatively slowly, a spider carrying the outer dial, a gear wheel on which the spider is mounted, an intermediate shaft, 70 a gear wheel thereon meshing with the dial gear wheel, a bevel gear wheel on the opposite end of the intermediate shaft, and a bevel wheel on the diagonal shaft that meshes with the first mentioned beveled gear 75 wheel so that the outer dial will revolve at a greater speed than the inner dial, the inner dial having graduations in inches, the graduations of the outer dial being in fractional parts of an inch.

5. In an indicating mechanism for rolling mills, the combination with a housing for the rolls of said mill, of a roll adjusting mechanism mounted on an upper portion of said housing, a pair of relatively movable 85 indicating dials rotatably mounted on another portion of said housing, and means for operatively associating said dials and said adjusting mechanism in such manner that the relative speed of rotation of said dials differs by a predetermined amount 90 upon the operation of said adjusting mechanism.

6. In an indicator for the adjusting screws of a rolling mill, the combination with an 105 adjusting screw mechanism, of a two part dial mounted for rotative motion, and driving means therefor inter-connecting the same and said adjusting screw mechanism in such manner that, upon the operation of 110 said adjusting screw mechanism, one of said dial parts moves at a speed greater than that of the other.

7. In combination, a driven member, a shaft having a dial thereon, said shaft and driven member being operatively associated, and a gear wheel mounted loosely on said shaft and carrying a second dial, said gear wheel and said driven member also being 115 operatively associated.

8. In combination, a driven member, a shaft having a dial thereon, said shaft and driven member being operatively associated and a gear wheel mounted loosely on said shaft and carrying a second dial, said gear 125 wheel and said driven member also being operatively associated in such manner that, upon the operation of said driven member, the relative motion of said dials differs.

9. In combination, a driven member, a 130

- shaft having a dial thereon, a gear wheel mechanism operatively associating said shaft and said driven member, a gear wheel loosely mounted on said shaft and carrying 5 a second dial, a second shaft, and gear wheel mechanisms operatively associating opposite ends of said second shaft with said gear wheel and with said driven member, respectively.
- 10 10. In combination, a driven member, a shaft having a dial thereon, a gear wheel mechanism operatively associating said shaft and said driven member, a gear wheel loosely mounted on said shaft and carrying 15 a second dial, the second dial surrounding the first mentioned dial, a shaft, and gear wheel mechanisms operatively associating opposite ends of said second shaft with said gear wheel and with said driven member,
- respectively, whereby, upon the operation 20 of said driven member, the relative motion of said dials differs.
11. In an indicating mechanism for rolling mills, the combination with a housing for the rolls of said mill, of a roll adjusting 25 mechanism mounted on an upper portion of said housing, a shaft driven by said adjusting mechanism, a second shaft mounted on a lower portion of said housing and carrying a dial, said first and second shafts being operatively associated, a gear wheel loosely mounted on said second shaft and carrying a second dial, a third shaft mounted adjacent to said second shaft and carrying gear wheels inter-connecting said second dial and said first-mentioned shaft. 30 35

PAUL C. HALDEMAN.
